UNITED STATES PATENT OFFICE

2,457,476

STEAM SIZING MACHINE

William Kaplan, Brooklyn, N. Y., assignor to
Wilbe Research Corporation, Brooklyn, N. Y.

Application November 20, 1946, Serial No. 711,041

2 Claims. (Cl. 223—70)

1

This invention relates to a steam sizing machine for knitted tubular cloth having a ribbed end portion which provides greater flexibility at the said portion and an object of this invention is to provide a steam sizing machine which permits steaming only the unribbed portion of the tubular cloth so as not to destroy the flexibility of the ribbed portion.

An object of this invention is to provide a steam sizing machine having an adjustable spreading frame for effecting the shaping of knitted fabric garments and by which various kinds of knitted articles of wearing apparel may be accurately shaped or fashioned.

Another object of this invention is to provide a machine supported solid skeleton spreading frame and means for raising and lowering the frame by a foot operated pedal, while both hands of the operator are free for mounting and adjusting tubular cloths on the spreading frame to be successively brought into overlying contacting relation with the steam table and steam treated from the exterior of the cloth and stretched to size.

Another object of this invention is to provide an adjustable machine supported frame for shaping a finished garment, whereby any desired shape may be imparted to a finished garment, the machine serving to support the frame while the hands of the operator are free for manipulating the garment.

Another object of this invention is to provide guide means adjustable on the spreading frame for limiting the portion of the cloth in contact with the steam table, whereby a ribbed portion of the garment may be kept out of contact with the steam so to retain the flexibility of the ribbed portion while steam treating the rest of the garment.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of the steam sizing machine.

Figure 2 is a side elevation of the machine.

Figure 3 is a front elevation of the machine.

Figure 4 is a plan view of the steam sizing machine shown in Figures 1 to 3 inclusive, with

2

an adjustable spreading frame shaped to conform to a finished garment such as a sweater.

Figure 5 is a perspective view of a connecting collar.

In the illustrated embodiment of the invention, the numeral 10 indicates a steam sizing machine for knitted tubular cloth and the like. The machine 10 comprises a base 11, uprights 12, 12 and a steam table 13.

The machine 10 comprises two vertical shafts 14 supported in brackets 15, 16, rearwards of the table 13. The brackets are secured to the base 11 and to the table 13 by bolts 17. The shafts are held in fixed position in the brackets by bolts 18. A guide bar 19 having apertures 20 at both ends is slidably mounted on extensions 21 of the shafts 14 above the table 13.

A treadle 25 is pivotally mounted on a pin 26. The rear end of the treadle 25 is pivotally connected by a pin 27 to an upright rod 28, shown in Figure 3. The upper end of the rod 28 is pivotally connected by a pin 29 to a collar 30 secured to the mid portion of the guide bar 19 by a bolt 31.

When the treadle 25 is depressed, the rod 28 is raised, and through the pivotal connections the guide bar 19 is raised in a vertical plane. Release of the treadle causes the guide bar to drop vertically due to its weight.

As best shown in Figure 1, the guide bar 19 has a plurality of threaded apertures 32 extending vertically therethrough. The apertures are equally spaced from the mid portion of the guide bar.

Slidably mounted on the guide bar 19 are two brackets 33, each having a bolt 34 passing therethrough and threaded in an aperture 32.

The brackets 33 have apertures 35 positioned crosswise of the guide bar 19 and above the said bar. Slidably mounted in the apertures 35 are two arms 36 which may be fastened to the brackets 33 by bolts 37. The forward ends of the arms 36 have loops 38.

The arms 36 jointly form a spreading frame on which tubular cloths such as knitted articles may be mounted and spread to size by moving the arms to or away from each other.

It will thus be noted that the two arms 36 function jointly as a solid skeleton cloth spreading frame 39 upon which tubular cloth may be mounted to be stretched and steamed to size.

As shown in Figures 1 and 2, it will be seen that collars 40 are slidably mounted on the arms 36 and may be secured thereto by screws 41. By adjusting the positions of the collars lengthwise of the arms 36 it is possible to limit the portion

of the cloth being steam treated. It is thus possible to mount a knitted tubular cloth 42 on the stretching frame and to leave the ribbed portion 43 of the cloth in overhanging relation with the steam table 13, so that the ribbed portion is not subjected to any steaming operation.

This arrangement is important because if no provision were made for guiding or limiting the unribbed portion of the cloth on the steam table and if the ribbed section would be on the steam table during the stretching and steaming operation, the ribbed material would not be able to retain its elasticity, a feature which is very desirable for knitted tubular cloths having ribbed sections incorporated therein.

The steam table 13 is hollow. The table has small apertures 45 throughout its upper surface. Steam is supplied to a steam chamber 46 in the table by a pipe 47 from any suitable supply.

A valve 48 in the pipe line 47 has a lever 49. A tension spring 50 suitably attached to the lever 49 maintains the valve 48 in closed position. A rod 51 is connected to the free end of the lever 49 at its upper end and to the free end of a treadle 52 at its lower end.

By depressing the treadle 52, the operator supplies steam to the table 13 and to cloth placed thereon in pre-arranged spaced relationship.

Figure 4 shows the steam sizing machine 10 with an adjustable solid skeleton spreading frame 55 shaped to conform to a finished garment such as a sweater.

The garment spreading frame 55 comprises two identically formed frame sections 56, 56, preferably made of wire or solid rod. Each section 56 has a straight portion 57. The frame sections are slidably mounted in the crosswise apertures 35 in the brackets 33 and fastened to the brackets 33 by the bolts 37.

The straight portions 57 extend to outwardly curved mid-sections 58, 58. At the termination of the midsections, the frame sections 58, 58 are again bent outwardly at 59 and then inwardly to cross each other with their ends 60, 60 terminating on opposite sides of a connecting collar 61 having two apertures 62, 62.

As shown in the drawings it is seen that by downpressing the pedal 25, the skeleton frame 39 or the skeleton frame 55 may be raised in considerably spaced-apart relation from and above the steam heated table or source of heat, to a point where the air is all around the tubular fabric. It is obvious that the removal of the fabric from the source of heat while retained in stretched condition on the skeleton frame will induce a quick cooling action on the stretched cloth.

In accordance with the patent statutes I have described and illustrated the preferred embodiment of my invention, but it will be understood

that various changes and modifications can be made therein without departing from the spirit of the invention as defined by the appended claims.

I claim:

1. In a steam sizing machine for steaming knitted tubular cloth from the exterior of the cloth, comprising a steam heated table having a horizontally positioned and perforated upper face, a guide bar supported parallel with said upper face and being mounted for up and down movements rearwardly of said steam table, a solid skeleton cloth spreading frame supported by said guide bar in a horizontal position, said guide bar in lowermost position being adapted to bring said spreading frame in contact with the perforated upper face of said steam table, and pedal means in front of said steam table for raising and lowering said spreading frame, while both hands of the operator are free for mounting and adjusting tubular cloth on said spreading frame to be lowered into overlying contacting relation with said table or raised into a position away from said steam table.

2. In a steam sizing machine for steaming knitted tubular cloth from the exterior of the cloth, comprising a steam heated table having a horizontally positioned and perforated upper face, a guide bar supported parallel with said upper face and being mounted for up and down movements rearwardly of said steam table, a solid skeleton cloth spreading frame comprising two spreading arms slidably supported by said guide bar in a horizontal position and being relatively adjustable thereon to and from each other and lengthwise of said steam table, said guide bar in lowermost position being adapted to bring said spreading frame in contact with the perforated upper face of said steam table, and foot-actuated pedal means in front of said steam table for raising and lowering said spreading frame, while both hands of the operator are free for mounting and adjusting tubular cloth on said spreading frame to be successively brought into overlying contacting relation with said table and said cloth steam treated and stretched to size.

WILLIAM KAPLAN.
